UNITED STATES PATENT OFFICE.

GEORGE A. SUCKFIELD, OF AVALON, PENNSYLVANIA, ASSIGNOR TO PRESSED STEEL CAR COMPANY, OF PITTSBURGH, PENNSYLVANIA, A CORPORATION OF NEW JERSEY.

CAR CONSTRUCTION.

Application filed May 19, 1926. Serial No. 110,057.

This invention relates to railway freight cars and has for an object the provision of a side wall construction for such cars, which comprises a metallic framing that is connected with the floor members or transverse underframing members of the car by means of a gusset plate or plates, and also comprises non-metallic side sheathing which is so disposed and secured to the framing that it may be removed or replaced without disturbing the framing connections or the connections between the framing and the gusset plate or plates.

Another object of the invention is to provide a composite side wall construction for railway freight car, in which the framing is metallic having non-metallic sheathing removably secured thereto, such framing effecting a splice joint or joints between the ends of the non-metallic sheathing intermediate the ends of the car.

These and other objects will be apparent from the following description.

Referring to the drawings in which like reference characters refer to like parts, Fig. 1 is a side elevational view of a portion of a railway car embodying the invention; Fig. 2 is a cross sectional view of the same taken on the line 2—2 of Fig. 1, portions of the side sheathing being omitted; Fig. 3 is a side elevational view of a portion of the car with the side sheathing removed; Fig. 4 is an enlarged sectional view taken on the line 4—4 of Fig. 2; and Fig. 5 is a sectional view taken on the line 5—5 of Fig. 3, the side sheathing being shown. Fig. 6 is a cross sectional view similar to Fig. 2 and showing a modified framing construction; Fig. 7 is an enlarged sectional view of a portion of the car taken on the line 7—7 of Fig. 6; Fig. 8 is a cross sectional view taken through a gondola car embodying the invention and Fig. 9 is an enlarged sectional view taken on the line 9—9 of Fig. 8.

Referring now in detail to the drawings the reference character 1 indicates a car body of the hopper type having a center sill 2, end walls 3, side walls 4, sloping end floors 5, and a transverse ridge 6. Between each of the sloping end floors and the transverse ridge, the center sill may be provided with the usual hood 7.

Each of the side walls 4 comprises a metallic framing 8 and a non-metallic sheathing 9 which sheathing in the present em-

bodiment of the invention comprises a plurality of longitudinally disposed boards placed edge to edge. The framing 8 is preferably of truss construction having spaced top and bottom members 10 and 11 respectively, which are connected by vertical and diagonal braces. At substantially the transverse center line of the car the vertical brace is in the form of two angles 12 having their flanges 13 directed outwardly and spaced apart and their flanges 14 extending in the direction of the length of the car. The transverse ridge comprises vertically disposed plates 15 which are suitably secured together and to the center sill and to the bottom member 11 of the side walls. This ridge also comprises ridge plates 16 which at their upper edges are secured to the plates 15 and slope downwardly therefrom in opposite directions and at their lower ends have discharge doors 17 hinged thereto. Above the top of the transverse ridge each of the plates 15, in the preferred embodiment of the invention, is in the form of an integral gusset 15^a the outer edge portion of which passes through the plane of the side sheathing and between the flanges 13 of the members 12 where it is secured to the flanges 13 by rivets or other suitable securing means. At each side of the car the ridge plates 16 are provided with flanges 18 each of which for a portion of its length is secured to a triangle plate 19 and for the remainder of its length is secured to the bottom member 11. Each of these plates 19 is secured to the bottom member 11 and to the flange 14 of one of the angles 12. At each end of the side wall the vertical brace is in the form of an angle 20 and between this brace and the brace at the transverse centerline of the car the vertical braces 21 and 22 as well as the diagonals 23 and 24 are preferably of flanged channel form. It will here be understood that members of any other suitable section may be substituted for those described.

At each side of the transverse centerline of the car the upper sheathing boards extend longitudinally of the body from the gusset 15^a to the vertical brace 20 and at their inner ends are secured to the flange 14 of one of the members 12 and at their outer ends are secured to the brace 20. Intermediate their ends, the sheathing boards are secured to the vertical braces 21 and 22 and

to the diagonals 23 and 24. The top sheathing board at intervals throughout its length is secured to the top member 10 of the framing. The lowermost sheathing board 5 is preferably secured at intervals throughout its length to the bottom member 11. The inner ends of some of the sheathing boards are secured to the flanges 18 of the ridge plates and to the plates 19 and 10 their outer ends are secured to angular members 25 which form parts of the sloping end floors 5. All of the sheathing boards are preferably secured to the metallic framing by bolts or other suitable removable 15 means, thus rendering it easy to remove or replace any or all of the sheathing boards.

In Figs. 6 and 7 of the drawings a modification of the invention has been illustrated in which the gusset 15^a at each side of the 20 car is in the form of a plate 26 which is secured to the transverse ridge by rivets or other suitable means.

In Figs. 8 and 9 the invention has been shown embodied in a gondola car and has 25 a gusset member 27 secured to the side framing and to one of the transverse floor or underframe members 28.

It will here be noted that, in a car constructed in accordance with the invention, 30 the sheathing can be removed and replaced without in any way disturbing the connections between any of the metallic framing members.

Having thus described the invention what 35 I claim as new and desire to secure by Letters Patent is:—

1. In a car wall, a metallic framing, a member secured to said framing and extending inwardly through the plane of said wall, and sheathing secured to said framing independent of said member.

2. In a car, a side wall, a metallic framing for said wall, side sheathing extending from each end of the car to points adjacent the 45 transverse center line of the car and remov-

ably secured to said framing, and a member secured to said framing and extending inwardly between the adjacent ends of said sheathing.

3. A railway car side wall comprising a 50 metallic framing and removable sheathing, spaced vertical members forming a part of said framing, and a gusset member secured to said vertical members and extending through the plane of said sheathing. 55

4. In a car, a side wall comprising a metallic framing and sheathing removably secured to said framing, said framing comprising spaced top and bottom members and vertical members connecting said top and bottom members, and a gusset member secured to said vertical members and extending inwardly through the plane of said sheathing. 60

5. In a car, a side wall comprising a metallic framing and sheathing removably secured to said framing, said framing comprising spaced top and bottom members, vertical members connecting said top and bottom members, plates connecting said vertical members and bottom member, sloping floor plates connected with said plates, and a gusset member secured to said vertical members and connected with said sloping floor plates, said gusset member extending 70 through the plane of said sheathing. 75

6. In a car body, a side wall framing comprising spaced top and bottom members, members connecting said top and bottom members, sheathing extending from each end of said body and terminating short of the transverse center line of said body, a transverse floor member, a gusset member secured to said connecting members and to said floor member, said gusset member passing between the adjacent ends of said sheathing, and means for removably securing said sheathing to said framing. 80 85

In testimony whereof I affix my signature
GEORGE A. SUCKFIELD
